UNITED STATES PATENT OFFICE.

RALPH V. SAGE, OF WESTMONT BOROUGH, PENNSYLVANIA.

CAR-DOOR MECHANISM.

1,085,300.

Specification of Letters Patent.

Patented Jan. 27, 1914.

Application filed August 29, 1912. Serial No. 717,708.

To all whom it may concern:

Be it known that I, RALPH V. SAGE, a citizen of the United States, residing in the borough of Westmont, in the county of Cambria and State of Pennsylvania, have invented certain new and useful Improvements in Car-Door Mechanism; and I do hereby declare the following to be a full, clear, and exact description of the invention, such as will enable others skilled in the art to which it appertains to make and use the same.

My invention relates to the door operating and locking mechanism for car-doors, and is adapted for use with gondola or flat bottom cars provided with flush doors, or with other types of dumping cars, and its object is to provide apparatus of the class described, which is simple in construction, convenient of operation and easily repaired.

An object of my invention is to provide a device wherein the door is held in a closed position by means independent of the lifting connections in case the lifting means should break or become disconnected.

To this end my invention consists of a lifting shaft connected to the door, and independent door-locking means adapted to be locked and unlocked by the rotation of the lifting shaft.

In the accompanying drawings forming part of this specification and in which similar characters refer to corresponding parts:—Figure 1 is a vertical transverse section taken on the line I—I of Fig. 2 through a portion of a gondola car-body, showing my invention applied thereto. Fig. 2 is a side elevation of a portion of a gondola car showing my mechanism as applied thereto. Fig. 3 is a detail transverse section taken on the line III—III of Fig. 2. Fig. 4 is a cross section of a pressed metal car-stake which I may use instead of the rolled shape shown in the other figures of the drawings. Fig. 5 is a perspective view of the bent plate forming a part of the construction.

For the sake of convenience of illustration and description, I have shown my improvement in connection with a flat bottom or gondola car, but the same can be used with a hopper bottom car or any other car having a swinging dumping door, and although the shaft is shown located longitudinally of the car, it may be mounted transversely or inclined, as will be readily understood by one skilled in this art.

Referring to the various characters of reference upon the drawings:—1 designates the operating-shaft, which, as shown, extends longitudinally of the car and is mounted in stirrup brackets 2 of substantially U-shaped form, the said shaft extending over the tops of the transoms, which transoms may either be composed of rolled channels 3 or of pressed metal as shown at 4. These flying transoms are riveted to the center sills 5 at their inner ends by means of angular brackets 6, if they are of rolled shape, or, if they are of pressed metal, by the integral inner flange of the same. The outer ends 70 of the flying transoms are riveted directly to the lower ends of the side-stakes 7 of the car. These stakes may be of rolled section of angular form, as shown at 7, or they may be of pressed metal as shown in cross section 75 in Fig. 4, or they may be of any other rolled or pressed shapes, as desired.

The corner shedding plate 8 has an upper vertical flange 9 attached to the lower edge of the car side plate and a lower vertical 80 flange 10 which forms the jamb of the door. This flange 10 may be bent inwardly, if desired, as shown in dotted lines in Fig. 1 so that the door will close against it.

The car door 11 is hinged at 12 on its inner side to the center-sills 5 and is operated by means of the door operating mechanism comprising the operating shaft 1 which has a worm or winding drum 13 mounted thereon and is connected to the bracket 14, attached to the door, by suitable lifting means, such as a chain 15, or other flexible connection which is arranged to wind or unwind upon the worm 13. The rotation of the shaft in one direction winds up these chains 95 and closes the doors, or, if operated in the opposite direction, unwinds the chains and opens the doors.

In order to lock the door in a closed position and take the strain off the lifting chains 100 15 and also prevent the door from accidentally opening, I provide one or more latches or bolts 16 of similar construction mounted slidably within the U-shaped stirrup brackets 2, which brackets have outwardly extending flanges 17 for attaching them to the shedding plate 8. A bent plate is fitted within the said U-shaped brackets having a portion extending vertically as at 18, and attached to one side of the bracket, a horizontal portion 19 slotted as at 20, and a downwardly extending end portion 21, thus

forming a box-shaped space for the reception of the latch 16, which has an upwardly extending lug 22 which is adapted to move within the slotted portion 20 and to contact with a tappet 23 mounted on the shaft 1.

5 The nose of the latch 16 is normally projected forward by means of a spring 24 and passes under the edge of the door, which may be reinforced with a striking plate 25. 10 If desired, an opening 26 may be made in the bottom of the U-shaped bracket in order to allow for the escape of any foreign substances which may otherwise clog the slideway.

15 The operation of the device is as follows:—Assuming that the door is closed, as shown in full lines in the drawings; the operating shaft 1 is turned in the direction of the arrow shown in Fig. 1, and in doing so 20 the straight face of the tappet 23 comes in contact with the lug 22 of the latch 16 pushing it backward and releasing the door; at the same time the chain 15 will be unwound and the door will swing downwardly and 25 inwardly to its open position. As a preliminary to the lowering of the door the straight face of the tappet 23 engages the contact lug 22 of the latch 16 during the first revolution or part revolution of the shaft 1 and 30 retracts the latch 16 to permit the door to be lowered, and after the door is partly lowered, the spring 24 pushes the latch farther forward than when the door is closed, so that at the next revolution of the shaft, the 35 tappet does not strike the contact lug. When the door is closed, however, the forward end of the latch bears against the striking plate 25 which holds it in position so that the tappet will engage the contact lug prior to opening the door as just described. In closing the door the operating 40 shaft is turned in the reverse direction, which will wind up the chain, and, owing to the beveled end of the latch, it will be pushed back when it comes in contact with the edge 45 of the door in passing the same and the latch will assume the position shown in the drawings, in which case the weight of the door at that side will be sustained by the latch 50 and its attachments.

While I have shown and described my invention in considerable detail, I do not wish to be limited to the exact construction specified, but may use such substitutions, modifications or alterations as fall within the scope of my invention, and as pointed out in the claims.

Having thus described my invention, what I claim and desire to secure by Letters Patent is:—

60 1. The combination with a hinged car-door, of an operating shaft mounted on the car body, flexible connections therefrom to the door, spring projected locking mechanism independently mounted on the car body

and retracted by the said operating shaft and arranged to support the door in its closed position.

2. The combination with a hinged car-door, of an operating shaft mounted on the car body, flexible connections therefrom to the door, a spring projected latch adapted to be retracted by the said operating shaft, said latch being independently mounted on the car body and arranged to support the door in its closed position.

3. The combination with a hinged car-door, of an operating shaft mounted in stirrup brackets on the car side, spring projected door-locking means mounted within the said stirrup brackets and adapted to be retracted from the operating shaft and arranged to support the door in its closed position.

4. The combination with a hinged car-door, of stirrup brackets attached to the car side, an operating shaft having its bearings therein, spring projected door-locking means mounted within the said stirrup brackets, adapted to be retracted by the rotation of the operating shaft and arranged to support the door in its closed position.

5. The combination with a hinged car-door, of an operating shaft having its bearings in stirrup brackets mounted on the car side, a latch adapted to operate within said stirrup brackets, a spring for normally projecting the latch beyond the edge of the car-door in its closed position, and a tappet secured to the operating shaft for retracting the latch to open the door.

6. The combination with a car provided with a swinging door, of a shedding plate, stirrup brackets having outwardly extending flanges attached to the said shedding plate, an operating shaft having its bearings in said stirrup brackets, a latch provided with means for normally projecting the same beyond the edge of the car-door, and a tappet secured to the operating shaft adapted to retract the latch in opening the door.

7. The combination with a car provided with a swinging door, of a shedding plate, stirrup brackets having outwardly extending flanges attached to the shedding plate, an operating shaft having its bearings in said stirrup brackets said shaft extending over the tops of the transoms of the car, a latch within said stirrup brackets, means for normally projecting the latch beyond the edge of the car door, and a tappet secured to the operating shaft within the stirrup brackets adapted to retract the latch in opening the door.

8. The combination with a hinged car-door, of an operating shaft having its bearings in stirrup brackets mounted on the car side, a latch having its slideway within said stirrup brackets, means for normally pro-

jecting the latch beyond the edge of the car door, a bent plate having a vertical portion attached to the inside of the stirrup bracket, a slotted horizontal portion forming the top 5 of the slideway of the latch, said horizontal portion being bent downwardly and adapted to transversely close the end of the slide-way; and a tappet secured to the operating shaft within the stirrup bracket adapted to 10 retract the latch in opening the door.

9. In a car-door locking mechanism, a hinged door, an operating shaft mounted in stirrup brackets on the car side, flexible connections therefrom to the door, a latch having 15 its slideway within said stirrup, a contact lug on said latch, means for normally projecting the latch beyond the edge of the door and adapted to retain the door in its

closed position; a bent plate having a vertical portion attached to the inside of the stirrup bracket and a slotted horizontal portion through which extends the contact lug of the latch, the outer end of said horizontal slotted portion being bent downward transversely to thereby close the end of the slideway; 25 and a tappet secured to the operating shaft within the stirrup bracket adapted to retract the latch by means of the contact lug in opening the door.

In testimony whereof I hereto affix my 30 signature in the presence of two witnesses.

RALPH V. SAGE.
